CLAIM

The ornamental design for a power inverter, as shown and described.

DESCRIPTION

FIG. 1 is an isometric top, front view of a first embodiment of a power inverter;

FIG. 2 is an isometric top, rear view thereof;

FIG. 3 is a front view thereof;

FIG. 4 is a left side view thereof;

FIG. 5 is a rear view thereof;

FIG. 6 is a right side view thereof;

FIG. 7 is a top view thereof;

FIG. 8 is a bottom view thereof; and,

FIG. 9 is a front view of an alternate embodiment of the power inverter.

The evenly spaced broken lines in the drawings are for the purpose of illustrating elements of the power inverter that form no part of the claimed design.

The power inverter is shown with a symbolic break in length. The appearance of any portion of the article between the break lines forms no part of the claimed design.

1 Claim, 9 Drawing Sheets
